ARTIFICIAL REED THATCHING, FOR ROOFING OR THE LIKE

Spencer P. Garrett, 4451 Vista del Monte,
Sherman Oaks, Calif. 91403

Filed June 16, 1971, Ser. No. 153,929

Term of patent 14 years

Int. Cl. D25—01

U.S. Cl. D13—1 J

FIG. 1 is a plan view of the design; and
FIG. 2 is a cross-section taken on the line 2—2 in FIG. 1.

I claim:

The ornamental design for artificial reed thatching, for roofing or the like, substantially as shown.
